WOVEN ENDLESS BELT

Gustav Walters, Middletown, Conn.

Application April 25, 1951, Serial No. 222,774

20 Claims. (Cl. 139—383)

1

This invention relates to improvements in woven-endless belts, and more particularly to woven-endless belts to be used as belts for pulley-travel mechanical purposes, such as drive belts, conveyor belts and abrasive belts, abrasive belts being those which have an abrasive such as rouge, emery, etc., adhered thereto for polishing, abrading, etc.

In the usual way of making woven-endless belts for pulley-travel mechanical purposes, the longitudinal strands are endless but the transverse strands are non-endless, and therefore such belts do not have selvage side edges as woven, with the result that such edges tend to unravel and destroy the side edge construction of the belt, in consequence of which such belts have to be thrown away due to this edge destruction.

One object of the invention, therefore, is to provide an improved woven-endless textile belt for pulley-travel mechanical uses, in which the non-selvage side edges thereof are of improved construction so as to give longer life to the edge-portions of the belt, and at the same time to not substantially interfere with the mechanical functioning action of the center or main or body portion of the belt.

With the above and other objects in view as will appear to those skilled in the art from the present disclosure, this invention includes all features in said disclosure which are novel over the prior art.

In the description and claims, various parts and steps are identified by specific terms for convenience, but they are intended to be as generic in their application as the prior art permits.

In the accompanying drawings forming part of the present disclosure, in which certain ways of carrying out the invention are shown for illustrative purpose:

Fig. 1 is a perspective view illustrating a woven-endless belt made in accordance with the present invention, mounted on a pair of pulleys;

Fig. 2 is an edge view of the belt illustrated in Fig. 1;

Fig. 3 is a top plan view of Fig. 2;

Fig. 4 is an enlarged sectional view on line 4—4 of Fig. 2;

Fig. 5 is a top plan view similar to Fig. 3 of a woven-endless tubular fabric comprising a plurality of belt sections which are ultimately to be cut into separate belt sections or belts;

Fig. 6 is an enlarged schematic view on line 6—6 of Fig. 5, illustrating the way that each longitudinal or weft strand of each ply of the body portion always remains in its own ply.

2

Fig. 7 is an enlarged schematic sectional view on line 7—7 of Fig. 2 illustrating one weave construction;

Fig. 8 is a schematic top plan view of the weave construction of Fig. 7;

Fig. 9 is a schematic top plan view similar to Fig. 8 of a modified weave construction;

Fig. 10 is a schematic top plan view similar to Fig. 9 of another modified weave construction;

Fig. 11 is a schematic fragmental view similar to the left end portion of Fig. 7, of another modified weave construction;

Figs. 12 to 17 inclusive are views similar to Fig. 11, of other modified weave constructions;

Fig. 18 is a sectional view of a fragment of a belt showing the left body and edge portions corresponding to Figs. 7 and 11 to 17 inclusive;

Fig. 19 is a view similar to Fig. 18 of a modified construction of edge portion;

Fig. 20 is a view similar to Fig. 19 of still another modified construction of edge portion;

Fig. 21 is a view similar to Fig. 12 of a modified weave construction in which the edge portions are of two-ply construction;

Fig. 22 is a view similar to Fig. 21 of a modified edge portion construction;

Fig. 23 is a sectional view of a fragment of a belt showing the left body- and edge-portions corresponding to Figs. 21 and 22;

Fig. 24 is a view similar to Fig. 22 of a modified weave construction in which the edge portions are of three-ply construction;

Fig. 25 is a sectional view of a fragment of a belt showing the left body and edge portions corresponding to Fig. 24;

Fig. 26 is a view similar to Fig. 11 of a modified weave construction in which the body portion is of three-ply construction; and

Fig. 27 is a view similar to Fig. 26 in which the body portion is of four-ply construction.

Referring to Figs. 1 to 8 of the drawings showing the form of the invention illustrated therein, the belt 30 is of woven-endless construction having a two-ply central or main or body portion 31 and two opposite edge-portions 32. The body portion of the belt can be said to be the belt proper which performs the mechanical functions for which the belt is intended, and the edge-portions are for the purpose of securing a satisfactory locking of the longitudinal edge strands against unraveling.

In the weaving of this belt, as shown in Fig. 5, a woven endless fabric 33 is woven with alternate body portions 31, and thinner portions 32a from which the edge portions 32 are formed. Each belt unit or belt 30 is made by cutting longitudi-

nally through the thin portions 32a as indicated by the broken lines-of-cut 34, to form the edge portions 32 of the belt 30. Ordinarily, the edge portions 32 of a belt will be given some further treatment to increase their resistance to unraveling, before such a belt is to be actually employed for a belt use. And the body portion of the belt may also be given further treatment before being used as a belt, all as will be more fully herein-after set forth.

Referring to Fig. 7 which is an enlarged schematic cross-sectional view on line 7—7 of Fig. 2, and to Fig. 8 which is a schematic plan view of Fig. 7, in which the longitudinal strands of the lower ply of the body portion are shown offset somewhat from their positions directly beneath the longitudinal strands of the upper-ply for clearness, the body portion 31 of the belt 30 is of two-ply construction consisting of the upper or outer ply 35 and the lower or inner ply 36, and each of the edge portions 32 is a single-ply construction. The upper ply 35 of the body portion 31 has endless longitudinal or weft strands 37 and the lower ply 36 has endless longitudinal or weft strands 38. Each edge-portion 32 has the endless longitudinal or weft strands 39, and the endless longitudinal strands 37, 38 and 39 are all woven with non-endless transverse warp strands or sets of warp strands 40, 41, 42 and 43 which extend integrally, continuously across the body portion and both edge portions as clearly shown in Figs. 7 and 8. The transverse warp strands 40 and 42 are binder or binder-warp strands in the body-portion 31, which bind the two plies 35 and 36 together and make this what is known as a solid-woven two-ply construction. Strands such as the strands 40, 41, 42 and 43 of Fig. 7, are known to those skilled in the art as warps or warp strands. But where warp strands or portions of warp strands such as 40 and 42 in the body portion 31, bind together two or more plies of woven material such as plies 35 and 36 of the body-portion 31, they are more particularly known as binder warps or binder-warp strands. And where it is desired to distinguish strands such as 41 and 43, and the portions of strands such as 40 and 42 which extend across the edge-portion 32, which do not bind two or more plies together, from binder-warp strands, the former are called ground warps or ground-warp strands.

In the claims, the term endless longitudinal or weft strand or strands is used in its sense as understood by those skilled in the art, that is, that although a weft strand is ordinarily of indefinitely great length except when it breaks during weaving or the weaving of a different size of weft strand is to be started, it is not necessary to have it of indefinitely great length if the picks constituting a weft strand or strands are constituted of weft strands, a majority of which are long enough to form at least three successive picks of the helix in which the weft strand extends in weaving a tubular fabric, so that the tubular fabric will have ample strength along the locations of the beginning and end of the picks.

Referring to Fig. 6 in which the plies 35 and 36 are represented in broken-line outline, it will be seen that the longitudinal weft strand 37 of the outer ply 35 of the body portion starts from the right hand side of Fig. 6, passes along through the outer ply of the lower layer of the tubular fabric 33, then around the outer ply of the upper layer of the fabric 33 and down at 37a to continue the helix formed by the weft-strand 37 until it finally is completed and emerges as

indicated at the right of Fig. 6 as the strand portion 37b. And similarly, the weft strand 38 of the inner ply 36 starts at the left side of Fig. 6 and proceeds around the inner ply 36 and up at 38a to continue the helix formed by the weft strand 38 until it emerges at the left of Fig. 6 as the strand portion 38b. It will be observed that the helix formed by the weft strand 37 never leaves its ply 35 while being woven in the fabric, until finally it emerges from the fabric as portion 37b. And similarly the weft strand 38 of the inner ply 36 continues around in the form of a helix while being woven in this ply 36 without at any time being woven in the ply 35, until finally it emerges as portion 38b at the left side of Fig. 6. While it is possible to have the weft strands cross back and forth so that they are woven first in one ply, then in the other ply, and then back in the first-mentioned ply of the body portion, and so on, I have found that this prior art method of weaving the weft strands in the plies of the body portion of a belt, results in an inferior construction of belt, considerably due to the stresses on the body portion of the belt in use, especially when the belt is run at high speed, causing a rupturing of the weft strand where it passes from one ply to another, with consequent more speedy destruction of the belt.

The modified construction of the belt 44 of Fig. 9 is the same as the belt construction illustrated in Figs. 7 and 8 except that instead of having the transverse strands woven as singles, they are woven as pairs of strands 45, 46, 47 and 48.

The modified belt construction 49 illustrated in Fig. 10 is the same as the belt construction illustrated in Fig. 9 except that although the pairs of transverse strands 50, 51, 52 and 53 are woven as pairs in the body portion 54 they are woven as singles 50a, 50b, 51a, 51b, 52a, 52b and 53a, 53b, in the edge portions 55, to thus bring about a better locking action than is accomplished in the construction of Fig. 9.

The modified belt construction 56 of Fig. 11 differs from the belt construction illustrated in Fig. 7 in that the longitudinal strands 57 and 58 of the two plies of the body portion 59 are shown as the same size as the longitudinal strands 60 of the edge portions 61, and by having the two sets of additional transverse strands 62 and 63.

The modified belt construction 64 of Fig. 12 differs from the belt construction of Fig. 11 in that the longitudinal strands 65 and 66 of the two plies of the body portion 67 are larger than the longitudinal strands 68 of the edge portions 69.

The modified belt construction 70 of Fig. 13 differs from the belt construction of Fig. 12 in that in the body portion 71, each of the shed groups of four longitudinal strands 72 and 73, of the two plies, takes the place of the single individual longitudinal strands 65 and 66 of the corresponding two plies of the belt construction of Fig. 12.

The modified belt construction 74 of Fig. 14 has pairs or groups of longitudinal strands 75 and 75a, in each shed of upper ply 76 of body portion 77, and corresponding shed pairs 78 and 78a in the lower ply 79 of the body portion 77.

The modified belt construction 80 of Fig. 15 has the shed pairs of longitudinal strands 81 and 81a of upper ply 82 of the body 83, and the shed pairs 84, 84a of the lower ply 85, each said longitudinal body strand being of the same size

as the longitudinal strands 88 of the edge portion 87.

The modified belt construction 83 of Fig. 16 has shed pairs of large longitudinal strands 89, 89a in the upper ply 90 of the body portion 91, and shed pairs of small longitudinal strands 92, 92a in the lower ply 93 of the body portion 91.

The modified belt construction 94 of Fig. 17 has each of the plies 95 and 96 of the body portion 97 woven with an over-two-under-two twill weave. The transverse strands 98, 99, 100, 101 form a repeat group in the upper ply 95, and the transverse strands 102, 103, 104, 105 form a repeat group in the lower ply 96. And the transverse strands 106 form binder strands for binding the two plies together. When the transverse strands reach the edge portion 107, they are woven in a plain over-one-under-one weave as shown in previous figures.

The belt 108 of Fig. 18, by having the edge portion 109 cut off relatively narrow as illustrated in Fig. 18, can have each portion 109, and the body portion 110 also, if desired, treated with rubber or other elastomer and vulcanized so that when an edge portion 109 rubs against a flange of a pulley or the like, it temporarily flexes out of the way and thus resists tendency of the longitudinal strands thereof to unravel, and thus maintain the belt in serviceable condition.

Or a belt 111 as illustrated in Fig. 19 can have the edge portion thereof cut from the woven fabric originally of a greater width and folded and cemented with rubber or other elastomer and/or sewed to form the edge portion 112.

Or a belt 113 as shown in Fig. 20 can have a still wider edge portion cut from the woven fabric and folded up and cemented and/or sewed to the edge portion 114.

Instead of having the edge portions of a belt of single ply construction, a belt such as belt 115 shown in Fig. 21 can have a two-ply body portion 116, and have an edge portion 117 having two plies 118 and 119, and these edge portion plies can be cemented and/or sewed together to provide a suitable non-raveling edge portion.

Or a belt construction 120 as illustrated in Fig. 22 can have the transverse strands 121 and 122, not only act as binder strands in the body portion 123, but continue on as binder strands to bind the two plies 124 and 125 of the edge portion 126 together.

The belt construction 127 of Fig. 23, illustrates a belt made in accordance with the two-ply edge constructions illustrated in Figs. 21 and 22 with the two plies 128 and 129 forming the edge portion 130.

The belt construction 131 illustrated in Fig. 24 has a two-ply body portion 132, and the three-ply edge portion 133 consisting of the three plies 134, 135 and 136.

The belt 137 of Fig. 25 has the three-ply edge portion 138 formed of the three plies 139, 140 and 141 of woven construction as shown in Fig. 24.

By proportioning the size of the average shed-area of the longitudinal strands in the edge portions as compared to the size of the average shed-area of the longitudinal strands in the body portion of the constructions of Figs. 21 to 25, it is possible to have the two plies or three plies, as the case may be, provide a thickness which will not be more than, but will be the same as or less than, the thickness of the body portion.

The belt construction 142 of Fig. 26 is made with its body portion 143 formed of three plies 144,

145 and 146, each shed area of each ply having a pair of longitudinal strands 147 and 147a therein. The edge portion 148 is a single-ply construction. The body portion 143 of Fig. 26 contains no ground-warp strands, but contains only binder-warp strands, and therefore as a result of the absence of ground-warp strands and the consequent absence of the restrictive action of ground-warp strands, the body portion has greater transverse elastic stretch sidewise or edgewise in the general plane of the body portion than if ground-warp strands were also present. The binder-warp strands 150a and 150b connect only the innermost ply 146 and the intermediate ply 145 together, and the binder-warp strands 150c and 150d connect only the intermediate ply 145 and the outermost ply 144 together.

The belt construction 149 shown in Fig. 27 is a four-ply body portion 150 and a single-ply edge portion 151.

Where the edge portion of a belt is to have only a single woven ply, whether such ply is to be straight with a cut edge, or folded with the folds sewed together, such single woven ply should be more flexible than the body portion. Where the edge portion is to consist of only a single woven ply that is straight and with a cut edge, it is important that it shall be more flexible than the body portion so that by treating the edge portions with rubber or other elastomer and vulcanizing them, when the edge portions rub against flanges of pulleys or the like, they will temporarily flex out of the way and thus resist tendency to unravel the longitudinal strands thereof, and thus maintain the belt in serviceable condition.

Inasmuch as belts made in accordance with the present invention always have at least two woven plies in the body portion, when it is desired to have a cut-edge straight single woven ply in each of the edge portions, it is possible to have ample flexibility in the edge portions as compared to the body portion, to inhibit unraveling action in the edge portions, even through the average shed area of the longitudinal strands of the edge portion is as great as or somewhat greater than the average shed area of the longitudinal strands of the body portion. A more definite definition of this relation is to say that the average shed area of the longitudinal strands in each edge portion should be substantially less than the average shed area of the longitudinal strands in the body portion multiplied by the number of plies in the body portion, and where there are two or more cut-edge woven plies in each edge portion, this still serves as a suitable definition of relationship of the edge and body portions. Where there are two or more cut-edge woven plies in the edge portion, the flexibility of the edge portion, for a given average shed area in the edge portion will be less than in the case of a single ply, but increased locking action against non-raveling action is given as a result of the cementing of the layers or plies together with rubber or other elastomer and/or the action of transverse binder strands when used, or sewing the plies together when that is done. And it is more advantageous to have the average shed area of the longitudinal strands of each edge portion not more than one half that of the average shed area of the longitudinal strands of the body portion multiplied by the number of woven plies in the body portion, and it is still more advantageous to have the average shed area of the longitudinal strands of each edge portion not more than one-fourth of the average shed area of the longitudinal strands of the body

portion multiplied by the number of woven plies in the body portion.

Belts in accordance with the present invention may have the longitudinal and/or transverse strands made of any suitable material, such as 5 cotton, nylon, etc.

My application Serial No. 222,772 filed April 25, 1951, describes means and method suitable for making woven-endless fabric from which belts in accordance with this invention may be made. 10

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A woven-endless pulley-travel belt having a woven-endless multi-ply body portion and two woven-endless edge portions, each edge portion being adjacent to and transversely beyond a side edge of the body portion in a direction away from the body portion; the body portion and edge portions each having endless longitudinal weft strands woven with non-endless transverse warp strands, the transverse warp strands extending continuously transversely across the body portion and across and beyond each side edge of the body portion in a direction away from the body portion and connecting the body portion and edge portions together; each edge portion having at least one woven ply; and the average shed-area of the longitudinal weft strands of each edge portion being substantially less than the average shed-area of the longitudinal weft strands of the body portion multiplied by the number of woven plies in the body portion.

2. A woven-endless pulley-travel belt having a woven-endless multi-ply body portion and two woven-endless edge portions, each edge portion being adjacent to and transversely beyond a side edge of the body portion in a direction away from the body portion; the body portion and edge portions each having endless longitudinal weft strands woven with non-endless transverse warp strands, the transverse warp strands extending continuously transversely across the body portion and across and beyond each side edge of the body portion in a direction away from the body portion and connecting the body portion and edge portions together; each edge portion having at least one woven ply; and the average shed-area of the longitudinal weft strands of each edge portion being not more than half the average shed-area of the longitudinal weft strands of the body portion multiplied by the number of woven plies in the body portion.

3. A woven-endless pulley-travel belt having a woven-endless multi-ply body portion and two woven-endless edge portions, each edge portion being adjacent to and transversely beyond a side edge of the body portion in a direction away from the body portion; the body portion and edge portions each having endless longitudinal weft strands woven with non-endless transverse warp strands, the transverse warp strands extending continuously transversely across the body portion and across and beyond each side edge of the body portion in a direction away from the body portion and connecting the body portion and edge portions together; each edge portion having at least one woven ply; and the average shed-

area of the longitudinal weft strands of each edge portion being not more than one-fourth the average shed-area of the longitudinal weft strands of the body portion multiplied by the number of woven plies in the body portion.

4. A woven-endless pulley-travel belt having a woven-endless multi-ply body portion and two woven-endless edge portions, each edge portion being adjacent to and transversely beyond a side edge of the body portion in a direction away from the body portion; the body portion and edge portions each having endless longitudinal weft strands woven with non-endless transverse warp strands, the transverse warp strands extending continuously transversely across the body portion and across and beyond each side edge of the body portion in a direction away from the body portion and connecting the body portion and edge portions together; each edge portion having only a single woven ply; and the average shed-area of the longitudinal weft strands of each edge portion being substantially less than the average shed-area of the longitudinal weft strands of the body portion multiplied by the number of woven plies in the body portion.

5. A woven-endless pulley-travel belt having a woven-endless multi-ply body portion and two woven-endless edge portions, each edge portion being adjacent to and transversely beyond a side edge of the body portion in a direction away from the body portion; the body portion and edge portions each having endless longitudinal weft strands woven with non-endless transverse warp strands, the transverse warp strands extending continuously transversely across the body portion and across and beyond each side edge of the body portion in a direction away from the body portion and connecting the body portion and edge portions together; each edge portion having only a single woven ply; and the average shed-area of the longitudinal weft strands of each edge portion being substantially less than the average shed-area of the longitudinal weft strands of the body portion multiplied by the number of woven plies in the body portion; and most of the longitudinal weft strands of the body portion being in shed groups.

6. A woven-endless pulley-travel belt having a woven-endless multi-ply body portion and two woven-endless edge portions, each edge portion being adjacent to and transversely beyond a side edge of the body portion in a direction away from the body portion; the body portion and edge portions each having endless longitudinal weft strands woven with non-endless transverse warp strands, the transverse warp strands extending continuously transversely across the body portion and across and beyond each side edge of the body portion in a direction away from the body portion and connecting the body portion and edge portions together; each edge portion having at least one woven ply; and the average shed-area of the longitudinal weft strands of each edge portion being substantially less than the average shed-area of the longitudinal weft strands of the body portion multiplied by the number of woven plies in the body portion; and most of the longitudinal weft strands of the body portion being in shed groups.

7. A woven-endless pulley-travel belt having a woven-endless multi-ply body portion and two woven-endless edge portions, each edge portion being adjacent to and transversely beyond a side edge of the body portion in a direction away from the body portion; the body portion and edge

11

to the general plane of the body portion, and each of said woven plies of each edge portion containing rubber-like material; and the average shed-area of the longitudinal weft strands of each edge portion being substantially less than the average shed-area of the longitudinal weft strands of the body portion multiplied by the number of woven plies in the body portion.

14. A woven-endless pulley-travel belt having a woven-endless multi-ply body portion and two woven-endless edge portions, each edge portion being adjacent to and transversely beyond a side edge of the body portion in a direction away from the body portion; the body portion and edge portions each having endless longitudinal weft strands woven with non-endless transverse warp strands, the transverse warp strands extending continuously transversely across the body portion and across and beyond each side edge of the body portion in a direction away from the body portion and connecting the body portion and edge portions together; each edge portion having at least one woven ply, at least certain of said transverse warp strands being woven in said body portion as binder-warp strands connecting the plies of the body portion together; and the average shed-area of the longitudinal weft strands of each edge portion being substantially less than the average shed-area of the longitudinal weft strands of the body portion multiplied by the number of woven plies in the body portion.

15. A woven-endless pulley-travel belt having a woven-endless multi-ply body portion and two woven-endless edge portions, each edge portion being adjacent to and transversely beyond a side edge of the body portion in a direction away from the body portion; the body portion and edge portions each having endless longitudinal weft strands woven with non-endless transverse warp strands, the transverse warp strands extending continuously transversely across the body portion and across and beyond each side edge of the body portion in a direction away from the body portion and connecting the body portion and edge portions together; each edge portion having at least one woven ply, certain of said transverse warp strands being woven in said body portion as binder-warp strands connecting the plies of the body portion together, and certain others of said transverse warp strands being woven only in the inner ply of said body portion; and the average shed-area of the longitudinal weft strands of each edge portion being substantially less than the average shed-area of the longitudinal weft strands of the body portion multiplied by the number of woven plies in the body portion.

16. A woven-endless pulley-travel belt having a woven-endless multi-ply body portion and two woven-endless edge portions, each edge portion being adjacent to and transversely beyond a side edge of the body portion in a direction away from the body portion; the body portion and edge portions each having endless longitudinal weft strands woven with non-endless transverse warp strands, the transverse warp strands extending continuously transversely across the body portion and across and beyond each side edge of the body portion in a direction away from the body portion and connecting the body portion and edge portions together; each edge portion having at least one woven ply, the said transverse warp strands being woven in said body portion as binderwarp strands connecting the plies of the body portion together; and the average shed-area of the longitudinal weft strands of each edge

12

portion being substantially less than the average shed-area of the longitudinal weft strands of the body portion multiplied by the number of woven plies in the body portion.

5 17. A woven-endless pulley-travel belt having
a woven-endless more-than-two-ply body portion
and two woven-endless edge portions, each edge
portion being adjacent to and transversely be-
yond a side edge of the body portion in a direc-
10 tion away from the body portion; the body por-
tion and edge portions each having endless longi-
tudinal weft strands woven with non-endless
transverse warp strands, the transverse warp
strands extending continuously transversely
15 across the body portion and across and beyond
each side edge of the body portion in a direction
away from the body portion and connecting the
body portion and edge portions together; each
edge portion having at least one woven ply, the
20 said transverse warp strands being woven in said
body portion as binder-warp strands connecting
the plies of the body portion together, certain of
said binder-warp strands connecting an interme-
diate ply and the innermost ply together, and
25 certain others of said binder-warp strands con-
necting an intermediate ply and the outermost
ply together; and the average shed-area of the
longitudinal weft strands of each edge portion
being substantially less than the average shed-
30 area of the longitudinal weft strands of the body
portion multiplied by the number of woven plies
in the body portion.

18. A woven-endless pulley-travel belt having a woven-endless three-ply body portion and two woven-endless edge portions, each edge portion being adjacent to and transversely beyond a side edge of the body portion in a direction away from the body portion; the body portion and edge portions each having endless longitudinal weft strands woven with non-endless transverse warp strands, the transverse warp strands extending continuously transversely across the body portion and across and beyond each side edge of the body portion in a direction away from the body portion and connecting the body portion and edge portions together; each edge portion having at least one woven ply, the said transverse warp strands being woven in said body portion as binder-warp strands connecting the plies of the body portion together, certain of said binder-warp strands connecting only the innermost and intermediate plies together, and certain others of said binder-warp strands connecting only the intermediate and outermost plies together; and the average shed-area of the longitudinal weft strands of each edge portion being substantially less than the average shed-area of the longitudinal weft strands of the body portion multiplied by the number of woven plies in the body portion.

60 19. A woven-endless pulley-travel belt having a woven-endless three-ply body portion and two woven-endless edge portions, each edge portion being adjacent to and transversely beyond a side edge of the body portion in a direction away from the body portion; the body portion and edge portions each having endless longitudinal weft strands woven with non-endless transverse warp strands, the transverse warp strands extending continuously transversely across the body portion and across and beyond each side edge of the body portion in a direction away from the body portion and connecting the body portion and edge portions together; each edge portion having at least one woven ply, the said transverse warp strands being woven in said body portion as

65

70

75

binder-warp strands connecting the plies of the body portion together, certain of said binder-warp strands connecting only the innermost and intermediate plies together, and certain others of said binder-warp strands connecting only the intermediate and outermost plies together; and the average shed-area of the longitudinal weft strands of each edge portion being substantially less than the average shed-area of the longitudinal weft strands of the body portion multiplied by the number of woven plies in the body portion, and the longitudinal weft strands of each ply of the body portion being in shed groups.

20. A woven-endless pulley-travel belt having a woven-endless multi-ply body portion and two woven-endless edge portions, each edge portion being adjacent to and transversely beyond a side edge of the body portion in a direction away from the body portion; the body portion and edge portions each having endless longitudinal weft strands woven with non-endless transverse warp strands, the transverse warp strands extending continuously transversely across the body portion and across and beyond each side edge of the body portion in a direction away from the body portion and connecting the body portion and edge portions together, and with the longitudinal weft

strands of each woven ply of the body portion always being woven exclusively in one woven ply and not also being woven in any other woven ply; each edge portion having at least one woven ply; and the average shed-area of the longitudinal weft strands of each edge portion being substantially less than the average shed-area of the longitudinal weft strands of the body portion multiplied by the number of woven plies in the body portion.

GUSTAV WALTERS.
